SEPARATION OF PHENOLS FROM HYDRO-CARBON DISTILLATES BY STEAM DISTILLATION

David William Milner, Leeds, England, assignor to Yorkshire Tar Distillers Limited, Barnsley, England

Application March 7, 1945, Serial No. 581,557
In Great Britain November 20, 1944

8 Claims. (Cl. 202—42)

1

This invention relates to the separation of phenols from hydrocarbon distillates.

The usual method of separating phenols from hydrocarbon distillates involves washing the distillates with a solution of caustic alkali and then acidifying the aqueous liquor in order to set free the phenols which are caused to separate as an oily layer.

The object of the present invention is to provide an improved process for the separation, without the employment of caustic soda or acids, of phenols from hydrocarbon distillates which contain hydrocarbon and phenols of closely related boiling points including such distillates obtained from a continuous tar still or petroleum still.

The invention consists, broadly, in subjecting such hydrocarbon distillates containing phenols which distill along with the hydrocarbons when such distillates are vaporized in the absence of steam to distillation in the presence of steam, whereby the major portion of the hydrocarbon components are distilled off with water in the form of an azeotropic mixture leaving a residue or giving rise in a later stage of distillation to a product having a relatively high phenols content.

The invention is particularly applicable to hydrocarbon fractions from continuous stills in which the boiling points of the hydrocarbons and phenols are closely related.

The invention is, however, also applicable to the treatment of mixtures of hydrocarbons and phenols in which there is a substantial difference in boiling points between the constituent hydrocarbons and phenols and is furthermore applicable to mixtures containing in addition to hydrocarbons and phenols other bodies such as tar bases.

Distillation in the presence of steam may be carried out in a continuous manner by running the mixture of hydrocarbons and phenols down a column up which steam is blown, the hydrocarbons being taken off at the top and the phenols at the bottom.

Alternatively, the process may be carried out by blowing steam into a body of a mixture of hydrocarbons and phenols in a still, in conditions in which the hydrocarbons will pass off and be condensed in the form of an azeotropic mixture, the phenols remaining behind.

The steam distillation may with advantage be carried out with the employment of a good fractionating column, products of a greatly improved and saleable quality containing phenols or tar acids can be produced directly.

2

In accordance with the invention, the separation may be effected by carrying out the distillation in a still in which is contained a relatively large proportion of water, so that there is always an excess of water in the still during the operation.

The still should preferably be fitted with a fractionating or dephlegmating column or a reflux or some other form of apparatus which will cause a portion of the distillate to reflux and thereby cause the separation of a distillate consisting mainly of hydrocarbons and water.

Conveniently, in accordance with the invention, the mixture of hydrocarbons and water distilling over and comparatively free from phenols, is run into a separator and the separated water returned to the column or other reflux device, or alternatively the distillate can be taken off and separated at a later stage in which case the addition of steam or water in a stepwise or continuous manner to the contents of the still must be made in order to keep an excess of water in the still.

Where the material to be treated contains 25 paraffinic as well as aromatic hydrocarbons, preferably fractions boiling within a temperature range of not exceeding 20° C. and, for instance, a range of 5° C. are treated in which case the paraffinic hydrocarbons will be concentrated in 30 the fraction arising towards the final stages in the distillation treatment in the presence of water.

The distilling operation is carried out until the 35 residual liquid in the still is sufficiently free from hydrocarbons for the purpose for which it is intended.

In the later stages of the distillation, some 40 intermediate fractions may be obtained containing the varying amounts of phenols and other impurities such as tar bases.

The tar bases may be removed by well-known methods from such fractions and the mixture of hydrocarbons and phenols returned to the still 45 for further treatment or added to a further charge, which is subjected to distillation in the presence of water.

By the process, in accordance with the invention, saleable phenol fractions can be produced 50 direct from certain mixtures of hydrocarbon oils containing phenols, tar bases, and other impurities.

The following particulars are given by way of 55 examples to illustrate the result which may be secured in accordance with the invention.

EXAMPLE I

A sample of coal tar naphtha distilling between 175° C. and 195° C. was placed in a still with a fractionating column and twice its volume of water added. The mixture was fractionated using a dephlegmator on the top of the column. The distillate was run into a separator and the water returned to the column as reflux until the separation no longer took place easily owing to the rising specific gravity of the oil in the distillate. At this point the whole of the distillate was taken off and the water separated later. The water thus separated can be used in the next charge.

Results

	Sp. Gr.	Tar Acids	Bases	Hydrocarbons
		Per cent	Per cent	Per cent
1 Charge 50 gallons	.968	33	5	62
2 20 1/4 gallons	.970	1	4	95
3 8 gallons	.950	8	8	84
4 5 gallons	.911	26	8	66
5 3 gallons	1.022	58	16	26
6 3 gallons		86	9	5
6 9 1/4 gallons residues	1.067	99.7	0.15	0.15

The residue was taken out of the still, the water separated and the oil distilled. Of the original charge 1% was left as a pitchy residue.

Thus about two-thirds of the hydrocarbons were recovered substantially free from phenols and about two-thirds of the phenols present were recovered as a marketable product. The intermediaries can be re-worked after removing the bases or they can be used for other purposes.

EXAMPLE II

A crude coal tar naphtha fraction distilling 170° to 175° C. was fractionated in the presence of water using a separator on the still head so that the water separated could be run back down the column as reflux.

The original naphtha tested as follows:

Flask distillation drop	169.5° C.	dry 175.5° C.	
Sp. gr.			.954
Paraffins		percent	14
Tar acids		do	34
Bases		do	1.2

On fractionation of 45 gallons of the above material under the conditions stated the following fractions were obtained.

	Sp. Gr.	Tar Acids	Bases	Paraffins
		Per cent	Per cent	Per cent
1 5 gallons	.932	1	Nil	1.5
2 do	.942	Nil	1	4.8
3 do	.943	Nil	1.5	4.75
4 do	.939	Nil	1.5	6.3
5 do	.880	1.5	2.0	36
6 do	.834	3.5	1.0	62
7 2 gallons	.816	4.5	0.5	69
8 13 gallons residues		99.56	0.14	0.3

The thirteen gallons of residues were marketable tar acids without any further treatment.

This represents about 85% recovery and the later intermediate fractions containing tar acids can be added to a further charge for re-treatment if desired.

The accompanying drawing is a diagram of a suitable form of apparatus for carrying the invention into effect.

1 is the feed pipe for the mixture of hydrocarbons and phenols of closely related boiling

75 concentrated form as fractions arising towards the final

points supplying them to column 2, to which steam is admitted by way of the pipe 3.

In the lower part of this column there is located a re-boiler 4.

The azeotropic mixture passes away from the column in the form of vapour by way of the pipe 5 to a condenser 6 and a separator 7 from which the lower layer, that is water and hydrocarbon, is returned by way of the pipe 8 to the column 10 and the separated hydrocarbon led away through the pipe 9. The distillation residue consisting largely of phenols in the column 2 passes out by way of the pipe 10 and is delivered to the distillation column 11 to which steam is admitted by way of the pipe 12. In this column there is a re-boiler 13.

The phenols constitute the distillation residue in this column and they are withdrawn by way of the pipe 14.

20 The vapours from the column pass out by way of the pipe 15 and are led to an analyser 16 and thence into a separator 17 the lower layer of liquid formed thereon being returned by way of the pipe 18 to the column 11.

A portion of the material separating in the separator 17 may be withdrawn by way of the pipe 19 for re-treatment in the column 2, being returned to that column by way of the feed pipe 1.

I claim:

30 1. The process of treating hydrocarbon distillates containing phenols which distill along with the hydrocarbons when such distillates are vaporized in the absence of steam which comprises subjecting such hydrocarbon distillates to distillation in the presence of steam, driving off as vapour the major portion of the hydrocarbon components with water in the form of an azeotropic mixture and recovering the phenols in the residual or higher boiling fractions.

40 2. A process as claimed in claim 1, in which distillation in the presence of steam is carried out in a continuous manner by running the hydrocarbon distillates containing phenols down a column up which steam is blown, the hydrocarbons being taken off at the top and the phenols at the bottom of the column.

45 3. A process as claimed in claim 1, in which steam is blown into a body of a mixture of hydrocarbons and phenols in a still whereby the hydrocarbons are driven off in the form of an azeotropic mixture and are condensed, the phenols remaining mainly behind as a residue.

50 4. The process of treating hydrocarbon distillates containing phenols which distill along with the hydrocarbons when such distillates are vaporized in the absence of steam which comprises subjecting such hydrocarbon distillates to distillation in the presence of steam, condensing the mixture of hydrocarbons and water distilling over and which is comparatively free from phenols, running the mixture into a separator whereby the hydrocarbons and water are separated and returning the separated water to the body of material undergoing treatment.

55 5. Process of treating hydrocarbon distillates containing paraffinic as well as aromatic hydrocarbons and in addition phenols which distill along with the hydrocarbons when such distillates are vaporized in the absence of steam which

70 comprises subjecting the hydrocarbon distillates containing both hydrocarbons and phenols in the form of fractions boiling within a temperature range to distillation in the presence of steam, collecting the paraffinic hydrocarbons in concentrated form as fractions arising towards the final

stages in the distillation treatment and the phenols are preponderately contained in the residue.

6. The process of treating hydrocarbon distillates containing phenols which distill along with the hydrocarbons when such distillates are vaporized in the absence of steam which comprises subjecting such hydrocarbon distillates to distillation in the presence of steam, driving off the major portion of the hydrocarbon components with water in the form of an azeotropic mixture, and thereafter subjecting the residual phenolic residue to distillation in the presence of water.

7. The process of treating hydrocarbon distillates containing phenols which distill along with the hydrocarbons when such distillates are vaporized in the absence of steam which comprises subjecting such hydrocarbon distillates to distillation in the presence of steam, whereby the major portion of the hydrocarbon components are distilled off with water in the form of an azeotropic mixture, thereafter interrupting the supply of steam and distilling off the phenols in the substantial absence of water.

8. The process of treating hydrocarbon distillates containing phenols which distill along with the hydrocarbons when such distillates are vaporized in the absence of steam which comprises subjecting such hydrocarbon distillates to distillation in the presence of steam, whereby the major portion of the hydrocarbon components are distilled off with water in the form of an azeotropic mixture, and thereafter collecting the 10 phenolic material remaining.
